POP-UP BOOK CONSTRUCTION

William B. Freedman, Hollis, and Joseph Gettler, Jr., Roslyn Heights, N. Y., assignors to Phillips Publishers, Inc., Newton, Mass., a corporation of Massachusetts

Application January 14, 1950, Serial No. 138,644

17 Claims. (Cl. 40—126)

1

It is a general object of our invention to provide new and improved methods or constructions useful in the fabrication of so-called "pop-up" books and the blanks used as the fillers or pages thereof. To that end, it contemplates particularly a new and improved way of fabricating said blanks and said books by the use of a multiple folded page construction which facilitates rapid and economical quantity production due to the structural simplicity and ease of assembly of said blank and book. It contemplates further a multiple page construction with pages of specified dimensions which preclude the possibility of a failure of the portrayed scene to extend as intended, or the possibility of an undesirable inversion thereof when the book is opened too wide.

Among the more specific objects are the provision of features affording the following advantages: Relative invulnerability to rough handling as by children, for example, by the provision of features permitting more than 180° opening of the book without damage to the "pop-up" structure. Elimination of the necessity for using cardboard stiffeners or glued parts in the final book assembly. Ease of fabrication of parts concealing the cut-out areas.

A pop-up construction is a device for producing a three-dimensional effect in a scene or drawing when the folio containing the scene or drawing is opened. There are various types of pop-up constructions which are known in the art. In one form of construction, and the one to which our invention is especially applicable, the book is viewed from the side, that is, the spine of the book is held horizontally, and the cover of the book is lifted away from the observer to raise the pop-up scene. In this form of construction, the pop-up scenes are generally die-cut directly from the book pages, each folio being produced from a single sheet, the pop-up structures are then folded up out of the double page, or folio, in position to extend into the desired arrangement of horizontal and vertical planes when the folio is opened approximately ninety degrees (90°).

In the normal method of binding a plurality of these pop-up folios into a book, the folios are arranged in proper order, and the first page of the first folio is glued to the inside of the cover, then between the back page of the first folio, and the first page of the second folio, a stiff cardboard sheet is inserted and the neighboring sides of the two pages are glued to the sides of the cardboard sheet. In all gluing operations the pop-up structure is held out of the way so as not to be glued down. Successive folios are similarly treated, and thus in effect all the folios are connected together, a single page in such an arrangement consisting

5 of the back page of a leading folio, a cardboard sheet, and the first page of a following folio, all glued together. The last page of the last folio is glued against the back cover, and the spine of the book may then be covered with a strip of cloth or paper.

Such construction is normally stiff enough to prevent the folios from being opened 180° or more. Over-opening, by which is meant opening to 180° or more, in this type of pop-up construction, results either in the pop-up structure being torn or being pulled flat into the die-cut sheet from which it was formed. When such a pop-up is pulled flat, the pop-up portion often 10 reinserts itself into the old cut lines and the edges of the pop-up frictionally engage with the edges of the cut-out area, which, of course, exactly match, and so the pop-up sticks in the pages of the book when the book is closed and opened 15 again, and does not erect itself. This effect is referred to as "inverting" the pop-up, and is to be avoided, if possible.

It is desirable to bind a pop-up book with what is termed a "mechanical binding" in the 20 trade. Mechanical bindings are of various types, but the types in most general use consist of either a spiral wire, or a series of plastic rings joined on a plastic strip or spine, the rings or wire being inserted in precut holes in the book 25 pages and the cover, and binding the pages and cover together much in the manner of a plurality of loose leaf rings, all connected together.

Such a construction is, of course, extremely 30 flexible and a book so bound may be laid out flat on the table, or the covers and pages thereof may be placed back to back so that the book, in effect, is opened a full 360°, and this without breaking the back of the book, or loosening the pages.

40 Mechanical binding is therefore most desirable in children's books, or advertising folders of a pop-up construction, because the book is more durable under rough handling and because its back cannot ordinarily be broken by over-opening. However, mechanical binding is disadvantageous for binding the type of pop-up folios that are glued to cardboard stiffeners and glued together in series, for when this type of pop-up 45 construction is bound in a mechanical binder, the extreme flexibility of the binding permits one to easily over-open pages of the book, and the pop-ups tear if they are glued in too tightly or otherwise may invert themselves.

50 Our construction of a pop-up blank adapted for mechanical binding into book form retains the durable features of a mechanically bound book, and permits individual assembly of the blanks in the book and the binding thereof without gluing folios together or using cardboard

stiffeners. Thus the book may be fully opened without injuring the pop-up. Our construction also provides a solid back wall behind the cut out folios so that the background for the pop-up scene does not have light showing through it. In addition, the width of the sections of our blank can be adjusted in relation to each other so that the pop-up scene is prevented from inverting itself, and the pop-up structure is resiliently supported and protected from damage by rough handling.

Other objects and advantages of this invention will be apparent from the following description of a preferred embodiment, and from the drawings, all of which are set forth for purposes of illustration, and in which:

Fig. 1 is a perspective view of a pop-up book opened to approximately 90°.

Fig. 2 is a view taken generally along the line 2—2 of Fig. 1.

Fig. 3 is a plan view of a pop-up blank.

Fig. 4 is an end view of a fully opened pop-up book.

Referring now to the drawings, as can best be seen by a comparison of Figs. 1 and 2, the pop-up book 11 comprises a plurality of pop-up blanks 12, a cover 13 and a mechanical binder 14. The mechanical binder consists of a reinforcing spine 15, to which is integrally affixed a plurality of binding rings 16, the ends of which overlap and retain the pages of the book and the cover in position. The mechanical binder 14 is generally made of a flexible resilient plastic material.

As shown in Figs. 1 and 2 the book 11 is opened flat, and the first pop-up blank 12 is opened approximately 90°, erecting the pop-up scene.

As shown in Fig. 3, the blank 12 is formed from a flat sheet 33 of paper, cardboard, or similar material. The sheet is die-cut along the plurality of solid lines 34, and scored along the plurality of dotted lines 35. The blank is also scored along the fold lines 17, 18, and 19. These fold lines divide the blank into four pages or sections, the left exterior section 20, the left interior section 21, the right interior section 22, and the right exterior section 23. As shown in Figs. 1 and 2, the blank is folded along the fold lines 17, 18, and 19 so as to form what may be termed a double folio. The interior sections 21 and 22 have been cut, scored and folded respectively along the series of solid lines 34 and the series of dotted lines 35 indicated in Fig. 3 to integrally provide a pop-up structure 24, in accordance with the usual method which is well known in the art.

As shown in Fig. 2, the pop-up structure 24 consists of a plurality of horizontal planes 25 and vertical planes 26, which are cut and bent from the interior sections, and which planes are integrally joined to each other at the fold line which marks their line of intersection. The pop-up structure, when decorated and colored as shown, produces a three dimensional picture which pops up, or is self-erecting when the folio is opened.

As shown in Fig. 1, the exterior sections 20 and 23 serve to conceal the cut out area 27 of the interior sections, from which the pop-up scene is cut, and thus prevent light from being seen through the back of the pop-up scene. The non-visible sides 31 and 32 of the exterior sections serve the normal functions of pages in a book and may carry a story or illustrative matter.

As shown in Fig. 3, the free or exterior ends 28 and 29 respectively of the exterior sections 20 and 23 are provided with a plurality of slots 30 adapted to receive the retaining rings 16 of the

binder, and so to be bound into the book as shown in Figs. 1 and 2. The book cover is also centrally provided with two rows of slots, indicated by numerals 36 and 37 in Fig. 2, adapted to receive the rings of the binder.

The blank is folded as previously described to form a double folio with the pop-up structure properly folded between the interior sections and the blank may then be bound in book form by running the binding rings through the slots provided in the exterior sections of the blank and in the cover. Alternately, the blank may be bound into a normally bound book, by stitching or gluing the ends of the exterior sections together, and placing this carcass in a cover by the same means.

It is within the scope of our invention to bind the folded blank into a mechanically or normally bound book by fastening in both the ends of the exterior sections and those portions of the interior sections that are clear of the pop-up scene and that lie in the center transverse fold line. Thus all the sections may be firmly secured into the binding; such a construction does not however permit our non-inverting feature to be incorporated.

In order to achieve our non-inverting feature in the pop-up construction where our blank is bound in a normally bound book the width of the two interior sections which comprise the pop-up section and the effective or bound width of that part of the two exterior sections which comprise the supporting section, must be carefully controlled. Where our blank is bound in a mechanical binder, in order to achieve our non-inverting feature, the width of the two interior sections which comprise the pop-up section and the effective width of the ring binder plus the effective or bound width of that part of the two exterior sections which comprise the supporting section, must be carefully controlled.

Note that in Fig. 3, the widths of each of the interior sections 21 and 22 is the dimension denoted by the symbol A/2. Thus the combined widths of the interior sections is A. The width of each of the exterior sections 20 and 23, from the fold line thereof to a line running tangent to the inside edge of the plurality of slots 30 is denoted by the symbol B/2. Thus the combined widths of the exterior sections is B.

As shown in Fig. 4, when the mechanically bound pop-up book is laid out flat, and the combined widths of the interior sections A is shorter than the combined widths of the exterior sections B plus the effective distance of separation between the lines of slots at the ends of the exterior sections due to the presence of the mechanical binder, which effective distance of separation is normally less than the diameter of the ring binder and is labelled C, then the folded interior sections with the folded pop-up structure therebetween forms an accordion-like spring suspended between the exterior sections which resists tension, or being pulled out flat. The exterior sections cannot lay flat because the folded ends thereof are joined to the shorter interior sections. Thus the interior sections will not be laid flat when the book is laid open and the pop-up sections are protected from inverting and damage due to over-opening of the book.

Alternately, when our blank is bound into a normally bound book, there is no mechanical binder to effectively separate the exterior sections, thus to achieve the required effect, the exterior sections are folded sufficiently longer than the in-

terior sections so that when the edges of the exterior sections are bound, the bound width of the exterior sections is sufficiently wide to supply the required additional difference in length between the exterior and the interior sections.

Since the sections or folios of our book, whether mechanically bound or normally bound, are not glued together between heavy covers, the weight of these will not be transmitted to an opened section or folio of our construction and operate to pull it open as often occurs in ordinary pop-up construction.

In our mechanically bound book, when the double folio is first opened, the ends of the longer exterior sections separate from each other and rotate around the binder rings. When the folio is fully opened, as shown in Fig. 4, the exterior sections are widely separated on the binder rings, and the blank is supported centrally by the ring binder, the exterior sections being under a compressive load, and the interior sections being under tension.

If external pressure is brought to bear downward on one side or the other of the face of the folio so as to press the pop-up into the interior sections, the exterior sections which are functioning as overly-long slim columns, bend or buckle under the compressive load long before the interior sections will tear or flatten completely under tension. Thus the pop-up structure, so supported, will resist being forced back into registration with the cut-out portion of the interior sections, and thereby inversion of the pop-up will be resisted and prevented. In fact, we have found that deliberate manipulation is generally required to flatten out the internal sections and so get the pop-up structures in a position where they will invert themselves.

As a general matter no precise formula can be given for the amount by which length B, in the case of a normally bound book, or length B plus C, in the case of a mechanically bound book, must be greater than length A, in order to obtain an effective non-inverting structure. The thickness of the paper from which the blank is cut, the width of the sections comprising the blank, the amount of area devoted to pop-up structure, the number of fold lines, and even the method of making fold lines, whether by scoring a solid line or scoring a broken line, will all affect the resiliency of the structure and vary the ratio between the lengths A and the lengths B or B plus C which is required to produce a non-inverting structure.

As an example, however, we have found that in producing a pop-up book, the following dimensions and specifications will produce a substantially non-inverting pop-up structure.

We have produced a pop-up book, having blanks made from what is known in the trade as 120 pound offset paper stock, and using a ring binding the outside diameter of which is approximately $\frac{5}{8}$ ". This diameter ring binding effectively spreads the slots in the exterior sections a distance of approximately $\frac{1}{4}$ ". This corresponds to the length C in Fig. 4.

The interior sections of our book are folded to be $7\frac{1}{2}$ " wide. Thus length A is 15". The exterior sections of our book, from the fold line to a line running tangent to the inside edge of the slots, are $7\frac{5}{8}$ " wide. Thus length B is $15\frac{1}{4}$ " wide and is approximately $\frac{1}{4}$ " greater than length A.

The sum of lengths B and C is therefore approximately $15\frac{1}{2}$ ", the percentage difference be-

tween lengths A and the sum of lengths B and C is above 3%. We have found these dimensions to produce a substantially non-inverting pop-up structure. The percentage difference between lengths A and the sum of lengths B and C may be of the order of 1%.

We claim:

1. A folio blank adapted to be bound as a folio into a book, said folio blank having three transverse fold lines thereon, marking said blank into four sections, the two interior sections being folded face to face along the intermediate of said lines, the two exterior sections being folded back against the backs of the interior sections along the others of said lines, said interior sections being cut and bent to provide a plurality of extensions in various horizontal and vertical planes which are self-erecting into a pop-up scene when the interior sections are opened.

2. A folio blank as in claim 1, in which the exterior edges of said exterior sections include a plurality of apertures by which the blank may be bound into a book.

3. A folio blank as in claim 1, in which the exterior edges of said exterior sections and those portions of the interior sections that are clear of the pop-up scene and that lie in the intermediate transverse fold line include a plurality of apertures by which the blank may be bound in a book.

4. A book containing at least one folio blank bound therein, said folio blank having three transverse fold lines thereon, marking said blank into four sections, the two interior sections being folded face to face along the intermediate of said lines, the two exterior sections being folded back against the backs of the interior sections along the others of said lines, said interior sections being cut and bent to provide a plurality of extensions in various horizontal and vertical planes which are self-erecting into a pop-up scene when the interior sections are opened.

5. A book as in claim 4, in which the exterior edges of the exterior sections of said blank include a plurality of apertures by which said blank is bound in said book.

6. A folio blank adapted to be bound as a folio into a book, said folio blank having three transverse fold lines thereon, marking said blank into four sections, the two interior sections being folded face to face along the intermediate of said lines, the two exterior sections being folded back against the backs of the interior sections along the others of said lines, said interior sections being cut and bent to provide a plurality of extensions in various horizontal and vertical planes which are self-erecting into a pop-up scene when the interior sections are opened, the bound width of said exterior sections being greater than the width of said interior sections whereby said exterior sections cannot lie flat when the folio is fully opened.

7. A folio blank as in claim 6, in which the exterior edges of said exterior sections include a plurality of apertures by which the blank may be bound into a book.

8. A book containing at least one folio blank bound therein, said folio blank having three transverse fold lines thereon, marking said blank into four sections, the two interior sections being folded face to face along the intermediate of said lines, the two exterior sections being folded back against the backs of the interior sections along the others of said lines, said interior sections being cut and bent to provide a plurality of exten-

sions in various horizontal and vertical planes which are self-erecting into a pop-up scene when the interior sections are opened, the bound width of said exterior sections being greater than the width of said interior sections whereby said exterior sections cannot lie flat when the folio is fully opened.

9. A book as in claim 8 in which the exterior edges of the exterior sections of said blank include a plurality of apertures by which said blank is bound in said book.

10. A book filler comprising a three fold, four section blank having an integral pop-up scene between the two interior sections of the blank, the free ends of the two exterior sections of the blank each being provided with a plurality of slots arranged in a line parallel to said ends to adapt said ends to receive a mechanical binder, the width of each exterior section measured from its folded end to the inside edge of the nearest slots being greater than the folded width of each interior section.

11. A blank adapted to be mechanically bound into a book, said blank having three transverse fold lines thereon, which mark said blank into four sections, the two interior sections being folded face to face, and additionally cut and folded to provide a plurality of extensions in various horizontal and vertical planes when the interior sections are separated, the two exterior sections being folded back against the backs of the interior sections, the free end of each exterior section being provided with a plurality of apertures disposed in a line parallel to said end, the width of each exterior section measured from its fold line to a line running tangent to the inside edge of the plurality of apertures being greater than the width of each interior section whereby when said exterior sections are mechanically bound into a book said plurality of extensions are substantially non-inverting.

12. The combination of a book cover, a mechanical binder, and at least one three fold, four section blank, the blank having an integral pop-up scene between the two interior sections thereof, the free ends of the two exterior sections of the blank being provided with a plurality of apertures arranged in a row and adapted to receive the mechanical binder, the cover being provided with a plurality of apertures adapted to receive the mechanical binder, said mechanical binder coupling the free ends of said blank and the cover together, the combined widths of the interior sections being less than the combined effective widths of the exterior sections plus the effective width of the mechanical binder when the interior sections are fully open whereby said pop-up scene will not invert when said interior sections are fully opened and then closed.

13. The combination of a book cover, a mechanical binder, and at least one three fold, four section blank, the blank having an integral pop-up scene between the two interior sections thereof, the free ends of the two exterior sections of the blank being provided with a plurality of apertures arranged in a row and adapted to receive the mechanical binder, the cover being provided with a plurality of apertures adapted to receive the mechanical binder, said mechanical binder coupling the free ends of said blank and the cover together, whereby said cover may be opened 360° without tearing the pop-up structures.

14. A folio blank adapted to be bound as a

folio into an assemblage of bound pages, said folio blank having three transverse fold-lines thereon, marking said blank into four sections, said four sections comprising two interior sections and two exterior sections, the width of each exterior section being at least equal to the width of its adjoining interior section, said interior sections having a plurality of cut-lines and fold-lines thereon to provide a self-erecting pop-up scene when said interior sections are cut and bound respectively along said cut-lines and fold-lines and said interior sections are folded face to face along the intermediate of said three transverse fold-lines.

15. A book as in claim 4, in which the exterior edges of said exterior sections of said blank and those portions of the interior sections that are clear of the pop-up scene and that lie in the intermediate transverse fold-line include a plurality of apertures by which said blank is bound in said book.

16. The combination of a cover, a mechanical binder, and at least one three-fold, four-section folio blank, said blank having three transverse fold-lines thereon marking said blank into four sections, the two interior sections being folded face to face along the intermediate of said lines, the two exterior sections being folded back against the backs of the interior sections along the others of said lines, the width of each exterior section being at least equal to the width of its adjoining interior section, said interior sections being cut and bent to provide a plurality of extensions in various horizontal and vertical planes which are self-erecting into a pop-up scene when the interior sections are opened, the cover and the exterior edges of said exterior sections and those portions of the interior sections of each of said blanks that are clear of the pop-up scene and that lie in the intermediate transverse fold-line being provided with a plurality of apertures, said mechanical binder passing through said apertures and coupling the exterior and interior sections of each of said blanks and the cover together.

17. The combination of a book cover, a mechanical binder, and at least one three-fold, four-section blank, the blank having an integral pop-up scene between the two interior sections thereof, the free ends of the two exterior sections of the blank and those portions of the interior sections that are clear of the pop-up scene and that lie along the center fold of said blank, and the cover, each being provided with a plurality of apertures arranged in a row and adapted to receive the mechanical binder, said mechanical binder coupling said sections, and said blank, and the cover together, whereby said cover may be opened 360° without tearing the pop-up structures.
